INVENTOR
Arthur C. Kleckner

By William Bradley Lee & McClellan

Attn:

UNITED STATES PATENT OFFICE.

ARTHUR C. KLECKNER, OF RACINE, WISCONSIN, ASSIGNOR TO WEBSTER ELECTRIC COMPANY, OF RACINE, WISCONSIN, A CORPORATION OF WISCONSIN.

IGNITION APPARATUS.

1,395,429.

Specification of Letters Patent. Patented Nov. 1, 1921.

Application filed September 18, 1920. Serial No. 411,035.

To all whom it may concern:

Be it known that I, ARTHUR C. KLECKNER, a citizen of the United States, residing at Racine, in the county of Racine and State 5 of Wisconsin, have invented certain new and useful Improvements in Ignition Apparatus, of which the following is a full, clear, concise, and exact description, reference being had to the accompanying drawings, forming 10 a part of this specification.

My invention relates to certain improvements applicable to those several types and styles of internal combustion engine ignition apparatus that may be comprehensively 15 classified as "unitary oscillating magneto ignition equipments." While ignition equipments of the general class mentioned differ somewhat, in so far as details of construction are concerned, they all comprise a plug 20 carrying make and break electrodes, and an oscillating magneto together with its appurtenant operating spring, or springs, push finger, or equivalent part that is engaged by an engine driven actuator, and a trip finger 25 that serves to actuate the electrodes in timed relation to the magneto; the magneto and its aforesaid appurtenant parts being mounted upon a supporting shelf or bracket that is carried by the plug; the plug, the magneto 30 and its aforesaid appurtenant parts, and the shelf or bracket being applicable to and removable from an engine as a unit.

More specifically my present invention 35 contemplates:

1st. The provision of an ignition equipment of the class mentioned which comprises improved and extremely satisfactory means for "cocking" the magneto.

2nd. The provision of an ignition equipment of the class mentioned wherein the magneto, bracket, the push finger and the trip finger are so constructed and arranged 40 that they may be applied to various styles of plugs, thereby enabling me to eliminate the 45 necessity for carrying in stock a multiplicity of different brackets or a multiplicity of push and trip finger combinations. In other words, I provide an arrangement of magneto, bracket, push and trip fingers that is 50 standard for all installations and which may be applied to plugs of various styles and sizes.

3rd. The provision in a magneto ignition equipment of the class mentioned of a composite structure which is operatively con-

nected with the magneto rotor and which provides the push finger, the trip finger, the means for disengaging the push finger from the engine driven actuator, and preferably the means for attaching the operating 60 springs to the magneto rotor, the several parts of this composite structure being so constructed and arranged that they may be assembled and secured together in a great variety of ways in order to meet the requirements of different installations. 65

These and other objects of the present invention will appear as the following detailed description progresses.

In the accompanying drawings illustrating 70 one embodiment of my invention,

Figure 1 is a top plan view of a unitary oscillating magneto ignition equipment constructed in accordance with my present invention. 75

Fig. 2 is a vertical sectional view taken on the line 2-2 of Fig. 1 and looking in the direction indicated by the arrows.

Fig. 3 is a disassembled view in perspective of the several parts of the composite 80 structure which provides the push finger, trip finger, the means for disengaging the push finger from the engine driven actuator and the means for attaching the operating springs to the magneto rotor. 85

Fig. 4 is a view illustrating how the said composite structure functions to effect the disengagement of the push finger and engine driven actuator and. 90

Fig. 5 is a fragmentary vertical sectional view taken on the line 5-5 of Fig. 2.

Similar characters of reference refer to similar parts throughout the several views.

For the purpose of convenience in description, I have used numerals to designate the 95 various parts of the unitary magneto ignition equipment and letters to indicate the actuator and its appurtenant parts which may properly be considered part of the engine. 100

In the drawings, at 10, I have illustrated the usual plug which is provided with the flange 11 and with a ledge 12. The plug, flange and ledge are cast as a single integral part, the plug being adapted to project into 105 an opening in an engine cylinder and arranged to be held in position by suitable bolts which project through the bolt holes 13-13 in the flange 11. Carried by the plug casting, are the usual stationary and 110

movable electrodes indicated respectively at 14 and 15. The stationary electrode is insulated from the plug casting and is provided with a clip 16 which is arranged to 5 coöperate with a conductor leading from the insulated terminal of the magneto. The movable or rocking electrode is provided with the arm 18 which, at the proper instant in the operation of the magneto, is 10 engaged by the magneto trip finger to effect the separation of the electrodes. Projecting laterally from the arm 18 is a pin 19 and interposed between the pin 19 and a cotter pin engaging in an aperture in the 15 plug ledge 12, is a tension spring 20, it being the function of this spring normally to hold the movable or rocking electrode in engagement with the stationary electrode and to oppose separation of the electrodes. In 20 terposed between the arm 18 and the plug casting is a compression spring 21, the purpose of which is to prevent the escape of pressure around the movable electrode by holding the beveled shoulder at the inner 25 end of the electrode tightly in engagement with a correspondingly shaped seat in the plug casting. This last mentioned expedient is well known in the art to which my invention relates and need not be illustrated 30 in detail.

I contemplate that the size and conformation of the plug casting and the disposition of its several parts, hereinbefore specifically mentioned, will vary considerably in 35 different installations. For instance, different engines require that the plug 10 have a variety of different sizes and shapes. In some installations, it is necessary that the ledge 12 be disposed vertically instead of 40 horizontally in order that the magneto may be carried in the position most suitable to the particular requirements of the engine with which it is used. A great number of variations in the plug casting and in the 45 construction and relative arrangements of its several parts which may be required in different installations, will at once suggest themselves to persons skilled in the art to which my invention relates. However, despite the respects in which the plug castings for use with various engines may differ, I find it desirable to provide each plug casting with a horizontally, or otherwise 50 suitably disposed ledge 12.

55 I shall now describe a magneto and apurtenant devices which may be more or less standard and which may be readily applied to for use in connection with any plug provided with a ledge of the kind hereinbefore mentioned.

The magneto generator is illustrated at 22 and while the particular type and construction of the magneto generator *per se*, is not important in so far as my present invention is concerned, I prefer that the magneto 65

shall be of the well known "Webster" tri-polar type. A magneto of this type is shown in Patent No. 1,180,489, dated April 25th, 1916.

The magneto shown in the accompanying 70 drawings comprises side plates 23—23 which provide bearings for the magneto rotor or inductor shaft 24. It will be noted that one of the side plates provides an exceptionally long bearing for the rotor shaft, this long 75 bearing being afforded by a hollow boss 25 which projects outwardly away from the side plate. The boss 25 projects freely through an aperture in a plate 26 which is rigidly secured to the adjacent side plate 80 23 by a plurality of screws 27—27.

While I have shown the plate 26 as being formed separate from the magneto side plate and rigidly attached thereto by screws 85 27—27, it will be understood that the plate 26 might, if desired, be made to constitute one of the magneto side plates. This variation in the arrangement is so obvious that it need not be illustrated.

The plate 26 preferably consists of a heavy 90 metal stamping and comprises laterally extending arms 26^a—26^a and a flange or base 26^b which is disposed at right angles to that portion of the plate which is bolted to the magneto side plate as hereinbefore described. 95 The flange or base 26^b is provided with suitably spaced apertures through which bolts 28—28 extend rigidly to secure the plate 26 to the plug ledge 12. It will be understood that the ledge 12 of every plug structure, designed to be used as a part of an equipment of my invention, will be provided with suitable bolt holes spaced to correspond to the bolt holes in the flange 26^b, to the end that any plate 26 and parts carried thereby may 100 be applied to the ledge 12 of any one of the plug structures.

I shall now describe the composite oscillating structure which is secured upon the magneto rotor shaft and which provides: 110

1st. The push finger.

2nd. The trip finger.

3rd. The means for disengaging the push finger from the engine driven actuator at the proper instant in the cycle of engine operation, and 115

4th. The means through which the operating springs are connected with the rotor shaft.

The several principal parts of the composite structure consist of sheet metal punchings which are perhaps most clearly illustrated at 30, 31, 32 and 33 in Fig. 3. Each of these punchings is provided with a central aperture 34. 120

Referring now, specifically, to the punching 30, it will be noted that it is somewhat elongated and is provided at its ends with two openings 35—35, these openings being designed to receive the spring roller posts 130

36—36 as shown in Fig. 1. Also formed in the punching 30 are nine apertures 37—37 which are equally apart and which are disposed in the circumference of a circle concentric with the opening 34.

The punching 31 is provided with a truly circular peripheral surface and is provided with three apertures 38—38 which are disposed 120° apart and are located on the 10 circumference of a circle concentric with the opening 34 of the punching 31.

The punching 32 is of considerably greater diameter than the punching 31 and is provided with a tooth 39 which, as will presently 15 appear, constitutes the magneto "push finger." The punching 32 is provided with six apertures disposed 60° apart and in the circumference of a circle concentric with the opening 34 of punching 32.

20 Punching 33 is provided with the arcuate surface 41 which is struck upon the same radius as the periphery of the punching 31. Furthermore punching 33 is provided with a tooth or finger 42 which, as will presently 25 appear, constitutes the "trip finger" which effects the separation of the make and break electrodes at the proper instant in the cycle of operation. Moreover punching 33 is provided with nine apertures 43—43 spaced 40° 30 apart and located in the circumference of a circle concentric with the opening 34 in the said punching 33.

Attention is directed to the fact that all 35 of the openings 37, 38, 40 and 43 of the several punchings are disposed equal distances from the centers of the circles in which they are arranged so that a plurality of apertures in contiguous punchings may be brought into register when the punchings are concentrically arranged as shown in Fig. 5. The composite structure comprising the punchings 30 to 33 both inclusive is secured together by three rivets 45 which extend through registering apertures in the several punchings.

45 Different installations require different relationships and different angular adjustments between the push finger 39 and the trip finger 42.

It will be seen that with the punchings 32 50 and 33 in the relationship shown in Fig. 3 whenever an aperture in the punching 33 is brought into registry with an aperture in the punching 32, two other apertures in the punching 33 will also register with apertures in punching 32. Thus with the punchings 32 and 33 in the relationship shown in Fig. 3, they are capable of being given nine different angular adjustments. However, the punchings may be placed in three relationships different from the one shown in Fig.

55 3. For instance, with the punching 32 in the position shown in Fig. 3 the punching 33 might be changed side for side. Again with the punching 33 in the position shown in Fig. 3, the punching 32 might be changed

side for side. Again both of the punchings might be changed side for side from the position shown in Fig. 3.

Since the apertures in the punchings 32 and 33 permit nine angular adjustments for 70 each of these relationships, it will be seen that I am enabled to get thirty-six different adjustments between the push finger 39 and the trip finger 42.

Since there are nine apertures in the 75 punching 30 it will be understood that any one of the thirty-six different combinations of punchings 32 and 33 may be given nine different angular adjustments with respect to the punching 30.

Since punching 31 is truly circular and is provided with three apertures disposed 120° apart, it will be seen that the apertures in this punching will always coöperate with the rivets regardless of the relative adjustments between the punchings 32 and 33 or between these last mentioned punchings and the punching 30.

80 After the several punchings 30 to 33 have been properly assembled and have been secured together to form a composite structure of the kind shown in Fig. 5, the opening afforded by the several central apertures 34 is converted by means of a suitable tool into a conical bore so that the composite 90 structure may be slipped over the tapered end of the rotor shaft as shown in Fig. 5. The composite structure is, furthermore, preferably provided with a suitable keyway adapted to coöperate with a Woodruff or 100 other key carried by the rotor shaft. The structure is conveniently held upon the shaft by a suitable nut as shown.

It will be noted that the arms 26^a of the stamping 26 are provided with roller posts 105 50 which are fitted into suitable openings in the said arms. Interposed between the rollers carried by the roller posts 50 and the rollers carried by the roller post 36 of the punching 30, are the comparatively heavy springs 110 51—51 which normally hold the composite structure and the magneto rotor in a definite angular position with respect to the field structure of the magneto.

I may suggest that when it is found desirable to place the punching 30 as close to the stamping 26 as has been illustrated in Fig. 1, a portion of the metal of the punching 30 at the edges of its ends next adjacent the springs is cut away (as shown in Fig. 1) 120 in order that the ends of the punching may not interfere with the free operation of the springs. This is, of course, an expedient which may or may not be employed as conditions require.

125 The engine driven actuator comprises a push rod A having one end thereof adjustably threaded into a casting B, a nut C being provided to maintain the desired adjustment between the push rod A and cast- 130

- ing B. The casting B is provided with a circular bore in which is fitted an eccentric D which is, in turn, rigidly mounted upon the shaft E. The shaft E is journaled in a bracket F and is provided with a hand piece G wherewith to turn the eccentric D with respect to the casting B. It is the purpose of the eccentric to permit the operator to advance and retard the occurrence of the spark.
- 5 If desired, the casting B may be provided with a suitable spring pressed ball H adapted to engage in either one of two recesses in the eccentric D so that the operator, without difficulty, may quickly adjust the eccentric to its proper positions for "starting" and "running." The bracket F is mounted upon any suitable moving part of the engine as, for instance, upon the exhaust valve operating rod indicated at I. The particular 10 bracket shown may be secured at any desired position upon the rod I by set screws J-J. The tension spring K is desirably interposed between the casting B and the bracket F, it being understood that this spring normally 15 tends to move the casting B and push rod A in a clockwise direction as the parts are viewed in Fig. 2.
- Secured upon that end of the push rod A opposite the casting B is a wedge or cam member indicated at L. This wedge or cam is secured to the push rod A by suitable rivets indicated at M. It will be noted that the wedge or cam member embraces the end of the push rod and that the side portions of 20 the wedge are inclined as indicated at 1-1.
- 30 Normally, the sides of the cam or wedge member L rest upon the arcuate surfaces of the punchings 31 and 41 as is clearly illustrated in Fig. 2. In this event, the end of the push rod lies adjacent the push finger 39 as is also clearly illustrated in Fig. 2. In the operation of the engine, when the exhaust valve I is moved to the right, (Fig. 2), the push rod is also moved to the right. 35 The end of the push rod engages the push finger 39 and moves the latter and parts connected therewith in a clockwise direction (Fig. 2) thus cocking the magneto rotor against the tension of the operating springs 40 51-51. Shortly after the push rod A engages the push finger 39, the inclined surfaces 1-1 of the cam or wedge member L, engage and ride upon the arcuate peripheral surfaces of the punchings 31 and 41. As a result of the 45 coöperation of the inclined surfaces of the wedge member with the arcuate surfaces of the said punchings, that end of the push rod which is in engagement with the push finger is raised as it moves to the right (Fig. 2). At 50 the proper instant in the cycle of engine operation, the wedging action between the surfaces 1-1 and the arcuate surfaces of the punchings 31 and 33 causes the push rod to be lifted out of engagement with the push 55 finger and when this occurs, the operating
- springs quickly snap the magneto rotor toward its normal position. As the rotor approaches the end of its recoil movement, the trip finger 42 forming part of the punching 33 engages the movable electrode arm 18 and causes the separation of the electrodes and the passing of a spark.
- It will be understood, of course, that in the assembly of the composite structure, the punching 33 has been given an adjustment 75 such that the trip finger 42 will effect the separation of the electrodes at the instant when the peak of the current wave generated in the magneto windings is attained.
- It will be understood, of course, that the 80 angle through which the magneto rotor is moved on its cocking movement may be regulated to a nicety by the inclination of the surfaces 1-1 of the member L.
- Having thus described my invention, what 85 I claim as new and desire to secure by Letters Patent of the United States, is:—
1. An ignition apparatus comprising an oscillatory push finger, an arcuate surface adjacent said push finger, said arcuate surface constituting part of the circumference of a circle having the push finger axis as its center, and an engine-driven actuator arranged to engage and move the push finger, the actuator being provided with means arranged to coöperate with said arcuate surface to disengage the actuator from the push finger when the latter has been moved through a predetermined angle. 90
2. An ignition apparatus comprising an 100 operating mechanism consisting of an oscillatory push finger, means fixed with respect to the push finger providing an arcuate surface adjacent said push finger, and a push rod for engaging said push finger, said arcuate surface being struck from a center coincident with the push finger axis, said push rod provided with a cam portion adapted to bear against said arcuate surface when the push finger is moved by the push rod, 105 the co-action of said cam portion and arcuate surface serving to disengage the push rod and push finger when the push finger has been moved through a predetermined angle. 110
3. An ignition apparatus comprising an oscillatory push finger, means fixed with respect to said push finger providing an arcuate surface concentric with the axis around which the push finger moves, and an 120 engine-driven actuator arranged to engage and move said push finger, the actuator being provided with a cam portion which co-acts with said arcuate surface to disengage the actuator from the push finger when the latter has been moved through a predetermined angle. 125
4. An ignition apparatus comprising an oscillatory push finger, means fixed with respect to said push finger providing two arc- 130

- uate surfaces, one on each side of the push finger, an engine-driven actuator arranged to engage and move the push finger, and means on said actuator arranged to co-act 5 with said arcuate surfaces to disengage the said actuator from the push finger when the latter has been moved through a predetermined angle.
5. An ignition apparatus comprising an oscillatory push finger, means fixed with respect to said push finger providing two arcuate surfaces, one on each side of the push finger, said arcuate surfaces being concentric with the axis of push finger movement, 10 an engine-driven actuator adapted to engage and move the push finger, and means carried by the actuator arranged to coöperate with said arcuate surfaces to disengage the actuator from the push finger when the 15 latter has been moved through a predetermined angle.
6. An ignition apparatus comprising an oscillatory push finger, means at the side of said push finger providing an arcuate surface concentric with the axis of push finger movement, an engine - driven actuator arranged to engage and move the push finger, and means carried by the actuator arranged to coöperate with said arcuate surface to dis- 20 engage the actuator from the push finger when the latter has been moved through a predetermined angle.
7. An ignition apparatus comprising an oscillatory push finger, an arcuate surface 25 immediately adjacent said push finger, said arcuate surface being struck from a center coincident with the push finger axis, an engine-driven actuator arranged to engage and move said push finger, and means carried 30 by the actuator arranged to coöperate with the arcuate surface to disengage the actuator from the push finger when the latter has been moved through a predetermined angle.
8. An ignition apparatus comprising an oscillatory push finger, means providing arcuate surfaces on opposite sides of the push finger, an engine-driven actuator arranged to engage and move the push finger, and a pair of cam portions depending from the 35 actuator, each of said cam portions adapted to coöperate with one of said arcuate surfaces to disengage the actuator from the push finger when the latter has been moved through a predetermined angle.
- 55 9. An ignition apparatus comprising an oscillatory member provided with a push finger, a second member fixed with respect to the first, said second member being provided with a trip finger, and having an arcuate surface concentric with the axis around which said members oscillate, an engine-driven actuator arranged to engage and move the push finger, and means carried by the actuator arranged to coöperate 60 with said arcuate surface to disengage the 65 actuator from the push finger when the latter has been moved through a predetermined angle.
10. An ignition apparatus comprising an oscillatory member provided with a push finger, a second member disposed immediately adjacent the first and provided with a trip finger, said means being provided with a plurality of equally spaced apertures arranged in concentric circles of the same 70 diameter, one of said members being provided with less apertures than the other, and rivets extending through registering apertures to secure said members together.
11. An ignition apparatus comprising an oscillatory and substantially disk-shaped member, provided with a push finger, a second substantially disk-shaped member disposed immediately adjacent the first and provided with a trip finger, a plurality of 75 equally spaced apertures in said members, said apertures being arranged in concentric circles of the same diameter, there being less apertures in one of said members than in the other, and rivets extending through 80 registering apertures serving to secure said members together.
12. In an apparatus of the class described, a composite oscillatory structure comprising a member provided with a push finger, a member provided with a trip finger, and a member constituting a spring yoke, equally 85 spaced apertures in each of said members, said apertures being arranged in concentric circles of the same diameter, there being less apertures in one of said members than in the other, and rivets extending through 90 registering apertures in said members to fasten the same together.
13. In an ignition apparatus, an oscillatory composite structure, spring means normally retaining said composite structure in a definite angular position, said composite structure comprising: a member provided with a push finger, a member provided with a trip finger and means for rigidly securing said members together in a plurality of 95 relationships and relative angular adjustments.
14. In an ignition apparatus, an oscillatory composite structure, spring means normally retaining said composite structure in a definite angular position, said composite structure comprising: a member provided with a push finger, a member provided with a trip finger and means for rigidly securing said members together in a plurality of 100 relationships and relative angular adjustments.
15. In an ignition apparatus, an oscillatory structure comprising a push finger, means carried with the push finger providing an arcuate surface struck from a center coincident with the axis of push finger movement, a push rod mounted at one end 105 on a moving pivot, the other end of the 110

- 6
- push rod being adapted to engage the push finger and being provided with a wedge riding upon the arcuate surface aforesaid, said wedge and arcuate surface coöperating 5 to disengage the push rod from the push finger substantially as, and for the purpose, set forth.
16. In an ignition apparatus, an oscillatory structure comprising a push finger, means carried with the push finger providing an arcuate surface, said arcuate surface being struck from a center coincident with the axis of push finger movement on a radius less than the distance from the push finger 15 tip to the axis of push finger movement, a push rod mounted at one end on a moving pivot, the other end of the push rod being adapted to engage the push finger and being provided with a wedge riding upon the 20 arcuate surface aforesaid, said wedge and arcuate surface coöperating to disengage the push rod from the push finger substantially as, and for the purpose, set forth.
17. In an ignition apparatus, an oscillatory structure comprising a push finger, means carried with the push finger providing an arcuate surface, all portions of said arcuate surface being closer to the push finger axis than is the tip of the push finger, 25 a push rod mounted at one end on a moving pivot, the other end of the push rod being adapted to engage the push finger and being provided with a wedge riding upon 30 the arcuate surface aforesaid, said wedge and arcuate surface coöperating to disengage the push rod from the push finger substantially as, and for the purpose, set forth.
18. An ignition apparatus of the class described comprising an oscillating member provided with an arcuate surface struck from a center coincident with the axis of 40 said oscillatory member, a push finger provided on said oscillatory member, side members disposed one on each side of said oscillatory member and secured thereto, each of 45 said side members provided with an arcuate surface struck from the same center as the arcuate surface of the first mentioned member, but on a shorter radius, a push rod having one end thereof mounted on a moving 50 pivot, and its other end adapted to engage said push finger, said last mentioned end of the push rod being provided with depending wedge portions which rest upon the arcuate surfaces of the side members, 55 said wedge portions coöperating with the arcuate surfaces of the side members to disengage the push rod from the push finger, and also, by lying on opposite sides of the first mentioned member, serving to retain 60 the push rod in operative relation to the push finger.

In witness whereof, I hereunto subscribe my name this 15th day of September, 1920.

ARTHUR C. KLECKNER.
